UNITED STATES PATENT OFFICE.

JAMES E. WRIGHT, OF WEST BAY CITY, MICHIGAN, ASSIGNOR OF ONE-HALF TO JOHN M. KELTON, OF BAY CITY, MICHIGAN.

METAL HOOP.

No. 827,773.

Specification of Letters Patent.

Patented Aug. 7, 1906.

Application filed August 15, 1904. Serial No. 220,840.

To all whom it may concern:

Be it known that I, JAMES E. WRIGHT, a citizen of the United States, residing at West Bay City, in the county of Bay and State of Michigan, have invented certain new and useful Improvements in Metal Hoops; and I do hereby declare the following to be a full, clear, and exact description of the invention, such as will enable others skilled in the art to which it appertains to make and use the same.

This invention is a metal hoop for barrels, casks, and similar packages.

The objects of the invention are to produce a hoop made of a band of metal shaped in such a way that the band may be made very thin and yet have great strength to resist both the tension produced by driving and the crushing force due to the force of the driving-tool upon the upper edge of the hoop, so that the hoop may be driven tight upon the barrel without danger of crushing or distorting the upper or driving edge of the hoop.

The construction of the hoop is such that no extra stiffening or reinforcing means are required, the necessary strength to resist the crushing in driving being attained by the form of the beaded upper edge of the hoop.

With these and other objects in view the invention consists in the device illustrated in the accompanying drawings, in which—

Figure 1 is a part sectional view of a barrel with a hoop in place, showing the relative position of the hoop and driving-tool while the hoop is being driven. Fig. 2 is a part sectional view of a barrel-stave, showing the hoop in place. Fig. 3 is an enlarged sectional detail of the hoop.

As is clearly shown in the drawings, the hoop consists in a strip or band of metal 1, having its upper part 2 bent outwardly, downwardly, and inwardly to form a beaded edge.

The essential feature of this invention lies in the construction and mode of operation of the beaded edge. It will be seen from Figs. 2 and 3 that by bending the upper portion outwardly the remaining width 1^a of the band bears completely throughout its area upon the barrel-staves. The greatest strength to resist distortion of the barrel when it is dropped or a heavy blow is dealt on the ends of the staves, tending to slide them past each other, is attained when the distance 1^a is greatest, and the greatest economy of material is attained when the amount of material

used in the bead 2 is least when compared with that used in the part 1^a. Therefore I prefer in practice to make the bead 2 of relatively small diameter, leaving as much as possible of the width of the band to form the part 1, which, as has just been explained, imparts truss strength to the barrel. In order to prevent distortion of the upper edge of the hoop, which tends to occur when the hoop is driven down tight by means of a hand or other driving tool 3, as shown in Fig. 1, I form the loop 2 so that its cross-section takes the form of an arch, the upper end of which is integral with the flat part 1^a and the lower end 2^a of which is bent inwardly, so as to butt against the outer face of the part 1^a. By this construction it is found in practice that extremely heavy blows may be delivered upon the hoop in driving, as indicated by the arrows in Figs. 1 and 3, without crushing or distorting the upper edge of the hoop. In fact, I have found by practical experience that by this curved or arched construction (in which the upper end of the arch is integral with the body of the hoop and the lower end of the arch butts against the hoop-body) any ordinary blow on the driving edge will not in the least distort the upper edge of the hoop even if the hoop be made of extremely thin metal.

By this construction I produce a hoop having a smooth upper driving-surface, smooth outer face that will not catch on obstructions, and an upper hollow driving edge that requires no reinforcing-wires or other supports. This hoop has extensive bearing area on the barrel, and although it may be made of extremely thin metal, being, therefore, much cheaper to manufacture, it combines with lightness of material great strength and great power of resisting distortion in driving.

What I claim as my invention, and desire to secure by Letters Patent, is—

1. As an article of manufacture, a hoop comprising a flat body portion, the entire inner transverse periphery of which engages the receptacle to which it is applied, and an approximately semicylindrical bead formed on the upper edge of the body portion to afford a broad, hollow, driving edge, the bead extending outwardly away from the body portion, thence downwardly and thence inwardly in an approximately straight line toward the body portion constituting a hollow

unreinforced arch, the inwardly-extending end of the arch abutting directly against the outer periphery of the body portion at substantially right angles thereto to brace the arch and resist distortion by the impact of a driving means.

2. As an article of manufacture, a hoop comprising a flat body portion, the entire inner transverse periphery of which engages the receptacle to which it is applied, and an approximately semicylindrical, hollow, unreinforced bead extending along the upper edge of the body portion and of a predetermined conformation to resist breaking down under the impact of a driving means, the free lower edge of the bead abutting against the body

portion at such an angle as to prevent its slipping.

3. The combination with a metallic hoop, of a hollow unreinforced rigid bead constituting a driving edge for the hoop, the bead being approximately semicylindrical, the free edge of the bead extending in a straight line toward and abutting the outer face of the hoop at substantially right angles thereto to prevent a slipping or a distortion of the bead.

In testimony whereof I affix my signature in presence of two witnesses.

JAMES E. WRIGHT.
